UNITED STATES PATENT OFFICE.

DAVID L. TEMPLE, OF NEW YORK, N. Y., ASSIGNOR TO WESTERN ELECTRIC COMPANY,
INCORPORATED, OF NEW YORK, N. Y., A CORPORATION OF NEW YORK.

TELEPHONE-EXCHANGE SYSTEM.

Application filed November 28, 1922. Serial No. 603,754.

To all whom it may concern:

Be it known that I, DAVID L. TEMPLE, a citizen of the United States of America, residing at New York, in the county of New York and State of New York, have invented certain new and useful Improvements in Telephone-Exchange Systems, of which the following is a full, clear, concise, and exact description.

10 This invention relates to a telephone exchange system and more particularly to a system in which connections are extended between subscribers' lines by machine switching equipment.

15 Subscribers' lines of a telephone exchange system are customarily divided into service groups in accordance with the manner in which the subscribers are to be charged for service, that is, certain of the lines, known 20 as flat rate lines, are permitted to make any number of calls within the exchange area for a fixed monthly rate, and other lines are permitted a fixed number of calls per month at a fixed rate, and are charged additionally 25 for all calls in excess of such number. Lines of this latter class are equipped at the central office with individual message registers for registering each successful call in order that the telephone company may be enabled 30 to make an additional charge for all calls in excess of the fixed monthly number. A third class of lines, usually terminating in pay station booths, are provided with coin boxes in which the calling subscriber is required to deposit a coin or token before obtaining a desired connection, the coin being 35 collected if the call is successful and refunded if it is unsuccessful.

40 In all exchange areas there are certain lines to which it is desirable and equitable to permit the extension of connections without charging the calling subscribers for service as by either operating the subscriber's message register or collecting a deposited coin or token. Such lines, for example, 45 are lines extending to the commercial offices of the telephone company, to fire stations, police stations and hospitals. In exchange areas where all connections are extended 50 manually by operators, it is obvious that the operators can take the necessary steps to

prevent the charging of such "free line" calls against calling subscribers as by refunding the coins deposited or by preventing the operation of the calling subscribers' 55 message registers.

In exchange areas in which connections are extended by machine switching mechanism, however, it is necessary to provide some means which will function automatically to give free service on connections to lines of the character above enumerated. This has usually been accomplished heretofore by the segregation of all lines of a free service character and by terminating them 60 in the terminal banks of certain final switches, such final switches being arranged to omit the usual service charge operation. With this method of handling calls to free lines, it is therefore necessary to reserve an 65 entire frame of switches having terminal facilities for from one hundred to five hundred lines depending upon the type of final switch used, whereas the number of such free lines in any given office rarely exceeds 70 fifty. It is thus apparent that such final selector switches are not efficiently employed and that a great economy in apparatus may be effected by terminating all lines alike in 75 the banks of regular final switches and supplying equipment individual to such free lines for nullifying the call charging operation.

It is, therefore, the object of the present invention to enable calls to be extended to 80 certain lines without charging the calling subscribers therefor, through the provision of means individual to each of such certain lines.

85 The principal feature of this invention resides in the provision of a circuit which may be inserted between a set of terminals in the final selector switch and the external circuit of a line, connections to which are to be given without charge to the calling subscriber. This circuit is arranged to trip machine ringing, and to apply ringing current to the called line without causing such changes in the exchange circuits as will 90 charge the calling subscriber for the call.

95 This and other features of the invention will be apparent from consideration of the 100

following description and the accompanying drawings,—in which Fig. 1 shows apparatus at a machine switching office of an exchange, comprising one of a plurality of subscribers' lines terminating therein, a line switch individual to the subscriber's line, a district selector for extending a connection from the subscriber's line to interoffice trunks extending to other offices of the exchange or on other switches in the same office, a sender selector switch, and an office sender shown diagrammatically within the dotted rectangle for controlling the operation of the district selector and the other switching apparatus of the exchange through which a connection may be extended. Fig. 2 shows a portion of the circuits of an incoming selector switch and final selector switch. Fig. 3 shows a circuit forming the basis for this invention, connected between the terminal banks of the final selectors of Figs. 2 and 4 and the line of a subscriber to which connections are to be permitted without charge, a diagrammatic representation of a portion of such called subscriber's line switch and the line of a subscriber, connections to which are charged for in the usual manner. Fig. 4 shows the calling end of an operator's cord circuit, a portion of a cordless incoming selector circuit and a diagrammatic representation of a final selector switch by means of which a connection may be extended from the operator's position to the subscribers' lines disclosed in Fig. 3.

35 *Description of apparatus and general method of operation.*

The line switch 106 of Fig. 1, is of the well-known step-by-step type controlled by magnet 102. The district selector 150 is of the so-called panel type shown in the patent to E. B. Craft and J. N. Reynolds, 1,123,696 issued January 5, 1915, but disclosed herein in a simplified form for the purpose of simplifying the disclosure of this invention. This switch has been illustrated as having but a single set of brushes 147, the assumption being made that the switch may be set to a desired group of terminals by a single selective movement under the control of the up-drive magnet 143. The selector switches 200, 250, 260 and 270 disclosed in Figs. 2 and 4 may also be of the type shown in the aforesaid patent.

55 The sequence switches 198 and 232 associated with the district selector 150 and with the incoming selector 200 and the sequence switch associated with the final selector switch 250, some of the cams of which have been illustrated, are of the well-known type disclosed in the patent to J. N. Reynolds and C. F. Baldwin, 1,127,808 issued February 9, 1915. For a complete description of the manner in which the apparatus disclosed in Figs. 1 and 2 functions, ref-

erence may be had to Patent 1,395,977, issued November 1, 1921 to F. A. Stearn and F. J. Scudder. Since the operator's cord circuit and the cordless position apparatus shown in Fig. 4 enter only incidentally into the disclosure of the present invention, it has not been thought necessary to show them in detail. A full disclosure and description of these circuits may be found in the application of J. W. Gooderham, Serial No. 417,422, filed October 16, 1920, Patent No. 1,506,743, Sept. 2, 1924.

The free line circuit shown in Fig. 3 is disclosed as inserted between the terminal banks of the final selectors 250 and 270 and an external line service toward which is to be accorded without charge. This circuit separates the subscriber's line from the switch terminals by condensers, which prevent the establishment of a direct current bridge across the tip and ring brushes of the final selector, upon the response of the called subscriber. Briefly, when the free line is seized, a slow-to-release tripping relay 300 is operated over the tip conductor of the circuit from ground applied at the incoming selector 200. This relay prepares a circuit for applying battery current to the ring conductor of the circuit for operating the ringing trip relay 230 at the incoming selector and causes the application of ringing current to the called line on the outgoing side of the condensers. Upon the application of ringing current to the called line, the circuit prepared by the slow releasing relay 300 is rendered effective for operating the ringing trip relay 230 and the circuit of relay 300 is opened so that the tripping circuit is effective only during the releasing period of slow-to-release relay 300. Upon the response of the called subscriber, the ringing current supplied to his line is cut off and talking current is supplied to the called line through supervisory relay 301. The closure of the circuit over the ring conductor of the free line circuit for tripping ringing current at the incoming selector, while applied for a sufficient period to trip the ringing current is not applied for a sufficient period to cause an effective reversal of current to the district selector to operate and lock the charging relay 168. Thus, no charge is registered against the calling subscriber for the connection.

Having now briefly described the invention and the apparatus employed it is thought that a clearer understanding of the invention will be had from a more detailed description of the manner in which the invention is practiced. Accordingly, a description will first be given of the manner in which a calling subscriber A establishes a connection with the line of subscriber B, it being assumed that the calling subscriber is to be charged for such connection. A de-

scription will then be given of the manner in which the subscriber A obtains a connection with the line of subscriber C without being charged therefor.

5 Establishment of a connection—calling subscriber charged therefor.

The calling subscriber A to initiate the establishment of a connection with the subscriber B, removes his receiver from the switchhook whereupon a circuit is established for the line relay 100 extending through the armatures and contacts of the cut-off relay 101 over the calling line loop. Line relay 100 upon energizing establishes a circuit for the stepping magnet 102 which in the well-known manner advances the wipers 103, 104 and 105 of the line switch 106 over the terminals of trunk lines extending to district selector switches. As soon as an idle district selector is found, a circuit is established for the cut-off relay 101 of the calling line, which may be traced from battery, through the operating winding of relay 110, cam contact 111, bank terminal 109 and test wiper 105 of line switch 106, to ground through the winding of cut-off relay 101 and the winding of message register magnet 112. Relays 110, and 101 energize in this circuit but magnet 112 being marginally wound, does not receive sufficient current at this time to energize. Upon the energization of cut-off relay 101, the circuit of the subscriber's line relay 100 is opened and the advance movement of the line switch is thereupon arrested.

Relay 110, upon energizing closes a circuit for advancing sequence switch 198 of the selected district selector 150 out of position 1 and into position 2, which circuit extends from battery through the magnet winding of sequence switch 198, cam contact 113 (1) and to ground at the right armature contact of relay 110. With sequence switch 198 in position 2, a circuit is established for the stepping magnet 116 of the sender finder switch SF, for advancing the sender finder in search of an idle office sender. The circuit of stepping magnet 116 may be traced from battery through the winding and armature contacts of magnet 116, cam contact 117 (2) and thence to ground at the left armature and contact of relay 118. During the hunting movement of sender finder SF, test wiper 119 advances over test terminals of office senders until the wiper 119 engages the test terminal of an idle sender, when a circuit is established for relay 118 extending from battery through the winding of this relay, wiper 119 and terminal 120 to ground. Relay 118 upon energizing opens the previously traced circuit of stepping magnet 116 thereby arresting the movement of the sender finder and closes a circuit for advancing sequence

switch 198 into position 3, which circuit extends from battery through the magnet winding of the sequence switch, cam contact 121 (2) and to ground at the right armature contact of relay 118.

Upon the association of an idle office sender with the selected district selector, an impulsing circuit is established between the office sender and the calling line over which circuit the calling subscriber is enabled, through the operation of his calling dials, to register the number of the desired line upon the registers of the sender, in the manner fully set forth in the patent to F. A. Stearn and F. J. Scudder, 1,395,977 referred to hereinbefore. This impulsing circuit may be traced from battery, through the register stepping relay 123, wiper 124, conductor 125, the left contact of cam 126 (1 to 3), bank terminal 108, wiper 104, thence over the calling subscriber's line loop, through his calling dial S, wiper 103, bank terminal 107, lower contact of cam 127 (1 to 3), conductor 128, wiper 129 and thence to ground.

With sequence switch 198 in position 3, a fundamental circuit is established between the control relay 131 of the district selector 150 and the selected office sender, which may be traced from battery, through the winding of control relay 131, cam contact 132 (3), conductor 134, wiper 135, winding of sender stepping relay 136, the contact of cam 130, which cam is associated with a sequence switch (not shown) of the office sender, the armature and back contact of counting relay 137, wiper 138, conductor 139, and thence to ground at cam contact 140 (3 to 4). Relays 136 and 131 energize in this circuit, relay 131 closing a locking circuit for itself through its left armature, cam contact 133 (3 to 4) and thence to conductor 134 and over the fundamental circuit previously traced. At its right armature and front contact relay 131 closes a circuit extending through cam contact 142 (3) and conductor 141 for advancing sequence switch 198 into position 4.

With sequence switch 198 in position 4, a circuit is established for the up-drive magnet 143 for advancing the brush set 147 of the district selector 150 in search of a group of trunk lines extending to the office of the exchange in which the desired line B terminates. The circuit of magnet 143 may be traced from battery, through the winding of magnet 143, cam contact 144 (4), and to ground at the right armature and front contact of relay 131. Magnet 143, upon energizing, presses the depending portion of switch shaft 145 against the constantly rotating up-drive roller 146, whereupon the switch shaft and the attached brush set 147 are driven upwardly.

As the brush set 147 approaches a posi-

tion immediately beneath the first group of bank terminals, shaft wiper 148 engages a conducting portion of commutator 149, whereupon a circuit is closed in shunt of the winding of sender stepping relay 136 which may be traced from battery, through the winding of control relay 131, the left armature and front contact of relay 131, cam contact 133 (3 to 4), cam contact 151 (4), conductor 152, commutator 149 and thence to ground through wiper 148. In response to the establishment of this circuit, sender stepping relay 136 deenergizes and in the well-known manner controls the circuits of the sender to count one impulse on the counting relays of the sender.

As the switch shaft 145 continues in its upward movement, the shaft wiper 148 engages an insulating portion of commutator 149 and the previously traced shunt circuit is thereupon opened again permitting the energization of sender stepping relay 136. Thus, during the continued upward movement of the switch shaft, the sender stepping relay 136 is intermittently energized and deenergized until the counting relay 137 becomes energized, when the office sender will be satisfied with respect to the office registration of the desired subscriber's line.

Upon the energization of relay 137, the previously traced fundamental circuit is opened thereby opening the circuit of control relay 131 and advancing the sequence switch of the sender to a position in which it controls the next selection. As soon following the opening of the fundamental circuit as the brushes of brush set 147 are centered upon the lowermost set of bank terminals in the selected group, shaft wiper 148 will engage an insulating portion of commutator 149 and relay 131 will become deenergized, opening the circuit of up-drive magnet 143 to arrest the upward movement of the switch shaft, and closing a circuit extending through cam contact 153 (4) and over conductor 141 for advancing sequence switch 198 into position 5.

With sequence switch 198 in position 5, the circuits of the district selector are prepared for the control thereof in its hunting movement for selecting an idle trunk in the selected group of interoffice trunks. A circuit is now established for relay 131 extending from battery, through the winding of this relay, cam contact 132 (5), and to ground at cam contact 154 (5), and at its right armature and front contact closes a circuit extending over cam contact 142 (5), and conductor 141 for advancing sequence switch 198 into position 6.

Under the assumption that the first trunk of the selected group, upon the bank terminals of which the brush set 147 is now resting, is at the time busy, relay 131 is maintained locked after sequence switch 198

leaves position 5, over a circuit extending through the left armature and contact of relay 131, cam contact 133 (5 and 5), cam contact 155 (5½ to 10), test brush 156, test terminal 157 and thence over multiples of test terminal 157, through the test brush 156 of a district selector similar to selector 150, which is at the time in engagement with the multiples of this trunk and to ground at a cam contact corresponding to cam contact 163.

With sequence switch 198 in position 6, the circuit of up-drive magnet 143 is again established over cam contact 144 (6) and the switch shaft 145 is again driven upwardly in search of an idle trunk in the selected group. So long as the test brush 156 engages the test terminals of busy trunks, the locking circuit of relay 131 is maintained and the circuit of up-drive magnet 143 remains closed. As soon, however, as test brush 156 engages the test terminals of an idle trunk, which it will be assumed is the trunk terminating in bank terminals 158, 166 and 167, the previously traced locking circuit of control relay 131 is opened and when the brushes of brush set 147 become centered upon the bank terminals of such idle trunk, relay 131 deenergizes. Until the brushes are so centered, relay 131 is maintained locked over its left armature, cam contact 133 (5 to 6), cam contact 161 (6), conductor 162, centering commutator segment 160, and to ground on shaft wiper 159. Upon the deenergization of control relay 131, the circuit of the up-drive magnet 143 is opened to arrest the upward movement of the switch shaft, and a circuit is established over cam contact 153 (6) and conductor 141, for advancing sequence switch 198 into position 8, in which position conductors 134 and 139 of the fundamental circuit extending to the office sender are connected over cam contacts 174 and 175 to the brushes 165 and 164 of the district selector 150.

During the setting of the district selector switch 150, relay 168 is maintained energized over a circuit extending from battery, through the winding of relay 168, the left-hand contacts of cam 169, wiper 170, armature and back contact of advance relay 171 of the office sender, and to ground at cam contact 172, and at its right armature and contact closes a circuit for energizing control relay 131 which is effective as soon as a sequence switch 198 reaches position 8. This circuit extends from battery, through the winding of relay 131, cam contact 173 (8) and to ground at the right armature of relay 168. Relay 131 is maintained energized until the office sender has functioned to completely establish the desired connection. With sequence switch 198 in position 8, busy potential is connected from ground

at cam contact 163 (7 to 17), over brush 156 to test terminal 158 for marking the selected interoffice trunk busy to other district selectors having access thereto.

5 Upon the extension of the fundamental circuit to the incoming selector switch 200, a circuit is closed from battery, through the right winding of relay 201, the right contacts of cam 202 associated with the sequence switch 232, conductor 203, resistance element 204, the upper contact of cam 205 (1 to 10) trunk conductor 206, bank terminal 167, brush 165, cam contact 174 (7 to 8), conductor 134, wiper 135, winding of 10 sender stepping relay 136, cam contact 130, the armature and contact of counting relay 137, wiper 138, conductor 139, cam contact 175 (7 to 8), brush 164, bank terminal 166, trunk conductor 207, the lower contact 15 of cam 208 (1 to 10), resistance element 209 and thence to ground at the lower contact of cam 210 (1 to 8). Relay 201 energizes in this circuit and at its armature and front contact closes a locking circuit for itself 20 extending through its right winding, lower contacts of sequence switch cam 202, the right armature and contact of relay 201, the contacts of sequence switch cam 211 (1 to 4), thence as previously traced over the 25 fundamental circuit. Relay 201 also, in the well-known manner advances sequence switch 232 to a position in which the switch shaft of the selector switch is advanced in its brush selection movement under the control 30 of the office sender.

During the upward movement of the shaft of the incoming selector switch, the sender stepping relay 136 is intermittently energized and deenergized in the well-known manner to energize and lock up successive pairs of counting relays until the office sender is satisfied with respect to the office brush registration set up thereon by the calling subscriber, when the counting relay 45 137 becomes energized and the sequence switch of the sender is advanced to the position in which it controls incoming group selection. Following the operation of relay 137, control relay 207 of the incoming selector deenergizes and in the well-known manner advances sequence switch 232 to arrest the upward movement of the switch shaft.

Upon the termination of the brush selection movement of the switch shaft of the incoming selector switch, a tripping magnet (not shown) is operated to trip the selected set of brushes upon a subsequent upward movement of the switch shaft and thereafter 50 in the well-known manner the selected set of brushes is advanced to a predetermined group of bank terminals in accordance with the setting of the thousands and hundreds registers of the office sender.

65 Upon the completion of the group selec-

tion movement of the incoming selector switch, the circuits of the incoming selector function in the well-known manner to select a trunk extending to an idle final selector switch. As soon as such idle trunk is found, 70 the sequence switch 232 of the incoming selector advances in the well-known manner to position 8, in which position the fundamental circuit is extended to the final selector switch. The fundamental circuit may 75 be traced in part from ground at the lower contact of cam 210 through resistance element 209, the lower contact of cam 208 (1 to 10), trunk conductor 207, thence as previously traced to the office sender and 80 through the winding of sender stepping relay 136, and returning over conductor 206, the upper contact of cam 205 (1 to 10) resistance element 204, conductor 203, the upper left contact of cam 212 (8), brush 213 85 of incoming selector switch 200 and thence through the control relay (not shown) of the selected final selector switch 250, to battery. A holding circuit is also established 90 at this time for relay 201 which may be traced from battery, through the right winding of relay 201, the lower contacts of cam 202, right armature and front contact of relay 201, the lower contact of cam 214 95 (7 to 8), brush 215, bank terminal 235, and thence to ground through the upper left and lower right contacts of cam 216. This holding circuit for relay 201 is maintained until the sequence switch of the final selector leaves position 8½ or until all of the 100 selecting movements of the final selector switch have been completed. Hundreds, tens and units selection are accomplished at the final selector switch 250 in accordance with the setting of the hundreds, tens and units registers of the office sender in the manner fully set forth in the patent to F. A. Stearn and F. J. Scudder, 1,395,977 hereinbefore referred to. The called line is now tested and if found to be idle, the sequence switch of the final selector advances into the talking position 15. 105

As soon as units selection is completed and the sequence switch associated with the final selector switch leaves position 8½, the previously traced holding circuit of relay 201 is opened at the lower contact of cam 216 and relay 201 in the well-known manner, causes the advance of sequence switch 232 associated with the incoming selector 110 200 out of position 8 into position 9. With sequence switch 232 in position 9, battery and ground at the incoming selector are reversely connected to the conductors 206 and 207 of the trunk circuit extending back to the district selector, and the office sender is thereupon caused to function in the well-known manner to operate the advance relay 171. The control relay 201 at the incoming selector, also energizes in this circuit 115 120 125 130

and advances sequence switch 232 out of position 9 into position 10.

Since at this time the office sender has completed its functions and relay 171 is operated, the shunt is removed from around resistance element 176 and the current now flowing through the winding of marginal relay 168 is reduced to such an extent that this relay deenergizes opening the circuit 10 of relay 131. Relay 131, upon deenergizing, closes a circuit extending over cam contact 153 (7 to 8) and conductor 141 for advancing sequence switch 198 into position 10. The office sender is now restored in the 15 well-known manner and disassociated from the district selector switch 150 whereupon it is rendered available for use in establishing other connections.

With sequence switch 198 in position 10, 20 relay 201 of the incoming selector is energized over a circuit which may be traced from battery through the right winding of relay 201, the right contacts of cam 202, conductor 203, resistance element 204, upper 25 contact of cam 205 (1 to 10), trunk conductor 206, bank terminal 167, brush 165, cam contact 177 (10), the upper right winding of repeating coil 178, the winding of polarized relay 179, the lower right winding 30 of repeating coil 178, cam contact 180 (10), brush 164, bank terminal 166, trunk conductor 207, the lower contact of cam 208 (1 to 10), resistance element 209, thence to ground at the lower contact of cam 210 35 (10). Current flowing in this circuit while in such a direction as to energize relay 201 does not flow through the winding of polarized relay 179 in such a direction as to cause its effective energization. Relay 201 upon 40 energizing causes the advance of sequence switch 232 into position 11 in the well-known manner.

With sequence switch 232 in position 11, 45 relay 201 is held energized over a circuit which may be traced from battery, through its left winding, the armature and back contact of marginal ringing trip relay 230, the contact of sequence switch cam 229 (10 to 18), the inner left armature and front contact of relay 201, the upper contact of cam 228 (2 to 18), sleeve conductor 227, bank terminal 158, brush 156 to ground at cam contact 163 (7 to 17). Ringing current is now applied to the called line B, it 50 being assumed that the final selector 250 found this line to be idle, over a circuit which may be traced from the source of ringing current 231 through the winding of relay 230, the left contacts of cam 202 (11 to 13), the right armature and contact of relay 201, the lower contact of cam 214 (11 to 14) brush 215, bank terminal 235, the upper contacts of cam 216, brush 221 and bank terminal 236 of the final selector 250 55 thence over the line of the called subscriber

B through the ringer 302 returning over bank terminal 237 and brush 224 of the final selector 250, the lower contacts of cam 225, bank terminal 226 and brush 213 of the incoming selector 200 to ground at the right 70 contact of cam 212 (11 to 13½).

Upon the response of the called subscriber, marginal relay 230 energizes and at its armature and back contact opens the holding circuit of relay 201. Relay 201 thereupon deenergizes, opening the circuit over which ringing current was applied to the called line at its right armature and front contact, and at its outer left armature and back contact closing a circuit for causing 80 the advance of sequence switch 232 out of position 11 into the talking position 16. With sequence switch 232 in position 16, a circuit is closed for supervisory relay 219 which may be traced from the non-grounded 85 terminal of battery, through the lower right winding of repeating coil 220, relay 219, the upper contact of cam 214 (14 to 16) thence over the subscriber's line loop as previously traced, returning through the lower contact 90 of cam 212 to ground through the upper right winding of repeating coil 220. Relay 219 energizes in this circuit and closes a circuit which is effective for operating the polarized relay 179 which may be traced 95 from battery, the upper contact of cam 210 (11 to 16), resistance element 209, upper contacts of cam 217 (11 to 16), lower left winding of repeating coil 220, the upper contact of cam 208, (11 to 16), trunk conductor 207, bank terminal 166, brush 164, cam contact 180 (10), the lower right winding 100 of repeating coil 178, the windings of relay 179, the upper right winding of repeating coil 178, cam contact 177 (10), brush 165, bank terminal 167, conductor 206, the lower contact of cam 205 (11 to 16), the upper left winding of repeating coil 220, resistance element 204, conductor 203, thence 105 to ground at the armature contact of relay 219.

A circuit is now established at the district selector for relay 181 which may be traced from battery over contact 182 of the circuit interrupting cam, the winding of relay 181, cam contacts 183 and 184, closed in position 10 and thence to ground at the contact of polarized relay 179, relay 181 upon 115 energizing, closes a locking circuit for itself independently of cam contact 182 and prepares a circuit for charging relay 168 which is effective as soon as the circuit cam moves to such a position as to cause the closure of its contact 185. Relay 168 upon energizing, closes a locking circuit for itself extending over the upper contacts of cam 169 and to ground through its own right armature contact, and at its left armature contact prepares a circuit over conductors 190 and 191, which is effective for charging a 120 125 130 135 140 145 150 155 160 165 170 175 180 185 190 195 200 205 210 215 220 225 230 235 240 245 250 255 260 call on the calling subscriber's message register 112 following the termination of the conversation and the movement of sequence switch 198 into position 17.

- 5 The calling subscriber A is now connected in a conversational circuit with the line of subscriber B over the conductors shown in heavy lines in Figs. 1, 2 and 3, the calling subscriber receiving talking current through 10 the left windings of repeating coil 178 and through the winding of supervisory relay 186 and the called subscriber receiving talking current through the right windings of repeating coil 220. During the continued 15 establishment of the talking circuit, the supervisory relays 186 and 219 are maintained energized over the calling and called lines respectively. Upon the termination of the conversation, the subscribers restore 20 their receivers to their respective switch-hooks whereupon relays 186 and 219 become deenergized. Relay 186 upon deenergizing closes a circuit extending over conductor 187 and cam contact 188 (5 to 16) for advancing 25 sequence switch 198 out of position 10 and into position 17. As soon as sequence switch 198 leaves position 16½ the previously traced circuit for relay 110 is opened at cam contact 111, but relay 110 is maintained energized over a circuit extending from battery 30 through its right operating winding, conductor 191, left armature contact of relay 168, conductor 190, cam contact 189 (17) bank terminal 109 and wiper 105 of line 35 switch 106, and thence to ground through the windings of cut-off relay 101 and message register magnet 112. Battery current is also connected through the winding of message register magnet 112 from battery 40 through cam contacts 192 and 193 closed in position 17, the left armature and contact and left non-inductive winding of relay 110, thence to ground through the winding of magnet 112 over the circuit previously 45 traced. Magnet 112 now receives sufficient current to cause its energization thereby causing the registration of a call on the calling subscriber's message register.

With sequence switch 198 in position 17, 50 a circuit is now established for relay 131 which may be traced from battery, through the winding of relay 131, cam contact 132 (17) and thence to ground through cam contact 154 (17). Relay 131 upon energizing 55 closes a circuit over cam contact 142 (17) and conductor 141 for advancing sequence switch 198 out of position 17 into position 18. As soon as sequence switch 198 leaves position 17, the circuit previously 60 traced through the windings of cut-off relay 101 and the message register magnet 112 is opened at cam contact 189, and the circuits associated with the calling subscriber's line and individual line switch are thereupon

restored to normal position in the well-known manner.

With sequence switch 198 in position 18, a circuit is established for the down-drive magnet 194 extending through contact 195 (18). This magnet, upon energizing, 70 presses the depending portion of switch shaft 145 against the down-drive roller 199 thereby causing a downward movement of the switch shaft into normal position. As soon as the switch shaft reaches its normal 75 position, shaft wiper 148 engages normal commutator segment 196, and a circuit is established from ground on wiper 148 through segment 196, cam contact 197 (18) and over conductor 141 for advancing sequence switch 198 in normal position. The 80 circuits of the district selector are now in normal position.

As soon as sequence switch 198 leaves position 17 busy ground potential is removed 85 from the test terminal 158 of the selected trunk 206, 207 and the restoration of the incoming and final selector switches to their respective normal positions is initiated. All 90 of the apparatus employed in the establishment of the connection is now in condition to be taken for use in establishing other connections.

Establishment of a connection—calling subscriber accorded free service.

It will now be assumed that the calling subscriber A desires a connection with the line C for which connection he should not be charged. The calling subscriber will proceed as hereinbefore described to dial the designation of the desired line whereupon the central office sender shown in Fig. 1 causes the operation of the district selector 150, the incoming selector 200 and the final selector 250 to make connection with the terminals 222, 223, 239 of the desired line C in the manner hereinbefore described.

When the brushes of the final selector switch 250 becomes positioned upon the terminals of the desired line, it being assumed that the line is at the time idle, a circuit is established for the sleeve relay 304, which may be traced from battery through the test brush 238 and bank terminal 239 of the final selector switch, conductor 240, the normal contacts of make-busy relay 303 to ground through the winding of relay 304. Relay 304, upon energizing, closes a circuit over the front contact of its inner right armature, through the winding of make-busy relay 303 to ground and in parallel over conductor 305, resistance 306 to ground through the windings of the cut-off relay 307 of the called line. Relay 304 upon energizing also disconnects battery at the back contact of its left armature and closes a locking circuit through the front contact of this arma-

ture extending from ground through the winding of relay 304, the alternate armature contacts of relay 303 and thence over conductor 240 to battery at the final selector switch. In this manner, the called line is made busy to all other final selectors which have access thereto. At its inner right armature and contact, relay 304 also prepares a circuit for the ringing relay 314 which becomes effective upon the energization of relay 300. At its outer right armature and contact, relay 304 prepares a circuit for the tripping relay 300 which becomes effective as soon as the sequence switch of the final selector 250 moves into its talking position and as soon as the sequence switch 232 of the incoming selector advances into position 11 for ringing as hereinbefore described.

With sequence switch 232 in position 11 and the sequence switch of the final selector switch in the talking position 15, the circuit of relay 300 may be traced from ground at the right contact of cam 212 (11 to 13½), brush 213, bank terminal 226, the lower contacts of cam 225, brush 224, bank terminal 223, conductor 308, conductor 309, the armature and back contact of relay 310, conductor 311, the outer right armature and contact of relay 304, the winding of relay 300 to battery at the outer left armature and back contact of relay 312.

With relays 304 and 300 both energized, the circuit of ringing relay 314 is established and may be traced from battery through the inner right armature and contact of relay 304, conductor 315, the winding of ringing relay 314, conductor 313 to ground at the left armature and front contact of relay 300. Relay 314, upon energizing, closes a locking circuit for itself extending from battery on conductor 315, through the winding of relay 314, the outer right armature and front contact of relay 314, to ground at the armature and back contact of ringing cut-off relay 317. Relay 314 is thus maintained energized independently of the operation of relay 300 until the called subscriber responds to the application of ringing current. Relay 314 at its inner right armature and front contact closes a circuit for relay 312 which may be traced from battery through the inner right armature and contact of relay 304, conductor 315, the inner right armature and contact of relay 314 to ground through the winding of relay 312. Relay 312 now energizes and locks to battery over conductor 305 independently of the contacts of ringing relay 314. With relay 312 energized, the circuit of relay 300 is opened at the outer left armature and back contact of relay 312 and relay 300 thereupon deenergizes. Being slow to release, however, battery is connected to the ring conductor 323 only during

the releasing period of relay 300 for the purpose of tripping machine ringing at the incoming selector switch 200. This circuit for tripping machine ringing may be traced from battery through the outer left armature and front contact of relay 312, resistance 321, the right armature and front contact of relay 300, conductor 322, conductor 323, bank terminal 222 and brush 221 of final selector switch 250, the upper contacts of cam 216, bank terminal 225 and brush 215 of incoming selector 200, the lower contact of cam 214 (11 to 14), the right armature and front contact of relay 201, the left contacts of cam 202 (11 to 13), the winding of marginal relay 230 and to the source of ringing current 231. Relay 230 now receives sufficient current to cause its energization and is instrumental in cutting off the ringing current and advancing sequence switch 232 to the talking position in the manner hereinbefore described. The releasing time of relay 300, however, is so adjusted that battery current is disconnected from conductor 323 before a circuit is established through the supervisory relay 219 at the upper contacts of cam 214 of the incoming selector switch of sufficient duration to operate relays 179, 181 and 168 in succession at the district selector so that it is not possible for the charging relay 168 to become energized at this time.

With the ringing relay energized, current from the ringing source 316 is connected to the external circuit of the called subscriber's line over a circuit which may be traced from the source 316 through the winding of marginal relay 317, the outer left armature and front contact of ringing relay 314, conductor 318 thence over the subscriber's line loop through the ringer 319, returning over conductor 320 to ground at the inner left armature and front contact of relay 314. Upon the response of the called subscriber and the removal of his receiver from its switchhook, marginal relay 317 receives sufficient current to cause its energization, whereupon the holding circuit of ringing relay 314 is opened and relay 314 becomes deenergized, disconnecting the source of ringing current from the subscriber's line. Upon the deenergization of relay 314, the initial energizing circuit of relay 312 is opened and relay 301 is connected with the conductors 318 and 320 of the called line. Talking current is now supplied to the called subscriber's substation over a circuit which may be traced from battery through the right winding of relay 301, the innermost left armature and contact of relay 312, the inner left armature and back contact of relay 314, conductor 320, thence over the subscriber's line loop, and returning through the outer left armature and back contact of

relay 314 to ground through the left winding of relay 301. Relay 301 now energizes connecting battery at its left armature to conductor 305 for holding relay 303 energized until the called subscriber hangs up his receiver. The initial energizing circuit for relay 303 is closed from battery over the front contact of the inner right armature of relay 304 through the winding of relay 303 to ground. This circuit is opened when the calling subscriber releases the selector switches 150, 200 and 250. However, the holding circuit of relay 303 makes it possible for the final multiple 239 of the called line to be thus maintained busy even though the calling subscriber releases the selector switches 150, 200 and 250.

The calling subscriber has now established a talking connection with the called subscriber's line C and the response of the called subscriber has had no effect upon the supervisory relay 219, since the external line conductors 318 and 320 of the called line are separated from the conductors 308 and 323 extending to the right windings of repeating coil 220 through the winding of supervisory relay 319, by means of condensers 324, 325 and 326. Since the supervisory relay 219 is not energized current is not reversed through the windings of polarized relay 179 at the district selector and consequently no message registration circuits are prepared for operating the subscriber's message register 112.

Upon the termination of the conversation and the restoration of the calling subscriber's receiver to its switchhook, the line switch 106, district selector 150, incoming selector 200 and final selector 250 are restored in the well-known manner and as hereinbefore described. Upon the restoration of the final selector switch 250, the circuit previously traced from battery over the test brush 238, bank terminal 239, and thence to ground through the winding of relay 304 is opened, and relay 304 becomes deenergized. Upon the restoration of the called subscriber's receiver to its switchhook, relay 301 deenergizes opening its armature contact thereby disconnecting battery from the conductor 305. Since now both relays 304 and 301 are deenergized, the holding circuits for relays 303, 312 and cut-off relay 307 are opened, and these relays thereupon de-energize. All of the circuits employed in establishing the connection are now in normal condition.

If the free line subscriber C initiates a call the line switch individual to his line leaves normal position in search of an outgoing trunk extending to a district selector in the manner hereinbefore described in connection with subscriber's line A. When the line switch leaves normal position battery current is connected through the off-normal

contacts 327 of the line switch, through resistance 306, conductor 305 to ground through the winding of make-busy relay 303. This relay, upon energizing, disconnects the winding of sleeve relay 304 from and connects battery potential to the multiples of test terminal 239 in the banks of all final selectors having access to the subscriber's line, over a circuit which may be traced from battery, through resistance 328, the left armature and back contact of relay 304, the armature and front contact of relay 303, conductor 240, thence to multiples of terminal 239. The subscriber's line C is thus marked "busy" to all final selectors having access thereto.

If a subscriber in a manual office wishes a connection with the subscriber's line C, for which no charge should be made, he first obtains a connection with the manual operator at the position indicated at O, Fig. 4, who, upon ascertaining the number of the line desired proceeds to obtain the assignment of a trunk circuit extending to a cordless operator's position of the machine switching office in which the desired subscriber's line terminates. Upon receiving the assignment of the trunk, the operator inserts the plug 241 of her cord circuit in the jack 242 of the assigned trunk circuit, whereupon a circuit is established from battery through the winding of sleeve relay 243 to ground over the sleeve conductors of plug 241 and jack 242. Relay 243, upon energizing, bridges the supervisory relay 244 across the strands of the cord circuit. A circuit is now established from battery through the right winding of relay 248, the normal right contacts of relay 249, the lower left winding of repeating coil 251, ring contacts of jack 242 and plug 241, the normal contact of ringing key 247, winding of supervisory relay 244, armature and contact of relay 243, normal contact of ringing key 246, tip contacts of plug 241 and jack 242, the upper left winding of repeating coil 251, the left armature and back contact of relay 249 to ground through the left winding of relay 248. Relay 248 energizes in this circuit and in the manner fully set forth in the application of J. W. Gooderham, Serial No. 417,422, Patent No. 1,506,743, hereinbefore referred to, causes the illumination of the lamp 252 to apprise the cordless operator that she may proceed to set up the designation of the desired line upon the keyboard of her sender and initiate the establishment of the desired connection through the medium of the cordless incoming selector 260 and the final selector 270.

Upon the seizure of the called line C by the final selector switch 270, a circuit is established from battery through test brush 257 and the bank terminal upon which it is resting, conductor 258, the winding of relay

310, the normal contacts of relay 303, to ground through the winding of sleeve relay 304. Relays 310 and 304 become energized, relay 304 causing the operation of relays 5 303 and 307 in the manner previously described. Relay 310 upon energizing opens the circuit previously traced through the winding of relay 300 to prevent the operation of this relay since upon a call of this 10 character it is not necessary to trip machine ringing. As relay 300 does not energize, relays 312 and 314 do not energize and therefore ringing current is not applied to the called subscriber's line from the 15 source 316.

Upon the establishment of the connection from the operator's position O to the desired subscriber's line C, the operator throws the ringing keys 246 and 247 for establishing a ringing circuit from the source 263, which may be traced over the alternate contact of key 247, ring contacts of plug 241 and jack 242, the lower left winding of repeating coil 251, the winding of ring-down relay 262, the upper left winding of repeating coil 251, tip contacts of jack 242 and plug 241, to ground at the alternate contact of key 246. Ring-down relay 262 responds to the ringing current and closes 30 a circuit from battery through the left winding of relay 249, the armature and contact of relay 262 to ground through the winding of ringing relay 259. Relay 249 energizes in this circuit disconnecting the 35 windings of relay 248 from the left windings of repeating coil 251 whereupon the circuit of relay 244 of the operator's cord circuit is maintained open after the release of ringing keys 246 and 247. Relay 248, 40 however, is maintained energized over a circuit extending from battery through its right winding to ground at the right armature and front contact of relay 249. Upon the energization of ringing relay 259 in 45 series with relay 249, ringing current is applied to the line of the called subscriber from the source 261 over the lower armature and front contact of relay 259, brush 255 and bank terminal of incoming selector switch 260, brush 256 and bank terminal of final selector switch 270, conductor 330, condensers 325 and 326, conductor 318, and thence over the subscriber's line loop 50 through ringer 319, returning over conductor 320, condenser 324, conductor 329, bank terminal and brush 253 of final selector switch 270, bank terminal and brush 254 of incoming selector switch 260, to ground 55 at the upper armature and front contact of relay 259.

Upon the response of the called subscriber during the silent interval when ringing relay 259 is deenergized, a circuit is established 60 for supervisory relay 264, which may be traced from battery through the right wind-

ing of relay 264, the lower right winding of repeating coil 251, the lower armature and back contact of relay 259, thence as previously traced over the called subscriber's line loop, returning through the normal contacts 70 associated with the upper armature of relay 259, the upper right winding of repeating coil 251 to ground through the left winding of relay 264. Upon the energization of supervisory relay 264, a circuit is established 75 from ground at the armature and contact of relay 248 through the armature and contact of relay 264 and the right winding of relay 249 for maintaining relay 249 energized.

Upon the termination of the conversation 80 and the restoration of the subscribers' receivers to their switch-hooks, the apparatus employed is restored in the following manner: Upon the restoration of the calling subscriber's receiver to its switchhook, the operator at position O receives the usual disconnect signal. When the called subscriber restores his receiver to its switchhook, the circuits previously traced through the windings of relay 264 are opened. Relay 264 90 upon deenergization, opens the holding circuit through the right winding of relay 249 and since at this time the circuit through its left winding is opened at the contacts of ring-down relay 252, relay 249 deenergizes 95 reconnecting the windings of relay 248 to the left windings of repeating coil 251 and thereby reestablishing the circuits through the supervisory relay 244 at the operator's position. With relay 244 energized, the circuit of the 100 calling supervisory lamp 245 is closed. As at this time, both the answering and calling supervisory lamps are lighted, the operator proceeds to release the connection by withdrawing the plug 241 from the jack 242. 105 From this point the apparatus employed in establishing the connection restores in the well-known manner.

What is claimed is:

1. In a telephone exchange system, a calling line, a called line, a second called line, call charging mechanism associated with said calling line, switching means for extending a connection from said calling line to either of said called lines, means associated with said switching means for applying ringing current to the line called, means associated with said switching means for operating said call charging mechanism following the successful establishment of a 110 connection between said calling line and one of said called lines, a relay individual to the other of said called lines operative upon the seizure thereof, a second relay operated thereby for opening the circuit of said first 115 relay, and a circuit controlled jointly by said relays for rendering said ringing current applying means inoperative, and for rendering ineffective said call charging operating means. 120

2. In a telephone exchange system, a calling line, a called line, a second called line, call charging mechanism associated with said calling line, switching means for extending 5 a connection from said calling line to either of said called lines, means associated with said switching means for applying ringing current to the line called, means associated with said switching means for operating said 10 call charging mechanism following the successful establishment of a connection between said calling line and one of said called lines, a slow releasing relay individual to the other of said called lines operative upon 15 seizure thereof, a second relay operated thereby for opening the circuit of said first relay and a circuit jointly controlled by said relays and effective during the releasing period of said first relay for rendering said 20 ringing current applying means inoperative, said circuit being closed for a period insufficient to operate said call charging operating means.
3. In a telephone exchange system, a calling line, a called line, a second called line, call charging mechanism associated with said calling line, switching means for extending 25 a connection from said calling line to either of said called lines, means associated with said switching means for applying ringing current to the line called, means associated with said switching means for operating said 30 call charging mechanism following the successful establishment of a connection between said calling line and one of said called lines, a slow releasing relay individual to the other of said called lines operative upon the seizure thereof, a second relay operated thereby for applying ringing current from said source directly 35 to said line, a third relay controlled by said second relay for opening the circuit of said first relay, a circuit jointly controlled by said first and third relays and effective during the releasing period of said first relay for rendering said first named ringing current applying means inoperative, and for rendering ineffective said call charging operating means, and means operative upon 40 the response of the called subscriber to completely disconnect said source of ringing current.
4. In a telephone exchange system, a calling line, a called line, a second called line, call charging mechanism associated with said calling line, switching means for extending 45 a connection from said calling line to either of said called lines, a source of ringing current, means associated with said switching means for applying current from said source to the called line, means associated with said switching means for operating said call charging mechanism following the successful establishment of a connection between said calling line and one of said called lines, means individual to 50 the other of said called lines for applying ringing current from said source directly to said line, a relay for controlling said last means and operative upon the seizure of said line, means controlled by said relay 55 for rendering said first named ringing current applying means inoperative, and for rendering ineffective said call charging operating means, and means operative upon the response of the called subscriber to completely disconnect said source of ringing current.
5. In a telephone exchange system, a calling line, a called line, a second called line, call charging mechanism associated with said calling line, switching means for extending 60 a connection from said calling line to either of said called lines, a source of ringing current, means associated with said switching means for applying current from said source to the called line, means associated with said switching means for operating said call charging mechanism following the successful establishment of a connection between said calling line and one of said called lines, a slow releasing relay individual to the other of said called lines operative upon the seizure thereof, a second relay operated thereby for applying ringing current from said source directly 65 to said line, a third relay controlled by said second relay for opening the circuit of said first relay, a circuit jointly controlled by said first and third relays and effective during the releasing period of said first relay for rendering said first named ringing current applying means inoperative, and for rendering ineffective said call charging operating means, and means operative upon the response of the called subscriber to completely disconnect said source of ringing current.
6. In a telephone exchange system, a calling line, a called line, a second called line, call charging mechanism associated with said calling line, automatic switching means for extending a connection from said calling line to either of said called lines, means associated with said switching means for applying ringing current to the line called, means associated with said switching means for operating said call charging mechanism following the successful establishment of a connection between said calling line and one of said called lines, condensers interposed in the other of said called lines between the substation thereof and said switching means, a relay individual to said latter called line operative upon the seizure thereof for rendering said ringing current applying means inoperative, and for rendering ineffective said call charging operating means, and means on the outgoing side of said condensers for supplying talking current to the substation of said called line.
7. In a telephone exchange system, a calling line, a called line, a second called line, call charging mechanism associated with said calling line, automatic switching means for extending a connection from said calling line to either of said called lines, means

associated with said switching means for applying ringing current to the line called, means associated with said switching means for operating said call charging mechanism following the successful establishment of a connection between said calling line and one of said called lines, a relay individual to said latter called line operative upon the seizure thereof for rendering said ringing current applying means inoperative, and for rendering ineffective said call charging operating means, a battery feed relay individual to said called line through which talking current is supplied to said called line, and means controlled by said latter relay for marking said called line busy to all other switching means having access thereto.

8. In a telephone exchange system, a calling line, a called line, a second called line, call charging mechanism associated with said calling line, automatic switching means for extending a connection from said calling line to either of said called lines, means

associated with said switching mechanism for applying ringing current to the other called line, means associated with said switching means for operating said call charging mechanism following the successful establishment of a connection between said calling line and one of said called lines, means individual to the other of said called lines and effective for a period sufficient to render said ringing current supplying means ineffective, but for a period insufficient to operate said call charging operating means, semi-automatic switching means for extending a connection to either of said called lines, and means operative upon the seizure of said second called line through said semi-automatic switching means for rendering said individual means inoperative.

In witness whereof, I hereunto subscribe my name this 24th day of November, A. D., 1922.

DAVID L. TEMPLE.
